United States Patent Office

Des. 181,016
Patented Sept. 17, 1957

181,016

GAS-FIRED UNIT HEATER OR SIMILAR ARTICLE

Edward A. Norman, Jr., Columbus, Ohio, assignor to
Norman Products Company, Columbus, Ohio, a corpora-
tion of Ohio

Application October 10, 1956, Serial No. 43,287

Term of patent 7 years

(Cl. D81—10)

FIG. 1.

FIG. 2.

FIG. 3.

Fig. 1 is a perspective view of a gas-fired unit heater or similar article showing my new design;

Fig. 2 is a top plan view on a somewhat smaller scale; and

Fig. 3 is a bottom plan view thereof, also on a smaller scale.

I claim:

The ornamental design for a gas-fired unit heater or similar article, substantially as shown.
